UNITED STATES PATENT OFFICE.

WILLIAM SEWARD BAIRD, OF CHICAGO, ILLINOIS, ASSIGNOR, BY MESNE ASSIGNMENTS, TO
BAIRD CORN HUSKER CO.

CORN-HUSKING MACHINE.

No. 892,208.

Specification of Letters Patent.

Patented June 30, 1908.

Application filed May 2, 1906. Serial No. 314,886.

To all whom it may concern:

Be it known that I, WILLIAM SEWARD BAIRD, a citizen of the United States, residing at Chicago, county of Cook, and State of Illinois, have invented certain new and useful Improvements in Corn-Husking Machines, of which the following is a description.

My invention relates to that general class of devices known as harvesters and to that particular class employed for harvesting corn by separating the ears from the standing stalks and the husks.

The object of my invention is to produce a convenient, efficient, and economical device of the kind described, one that may be depended upon to thoroughly clean the field even where a portion of the corn is down.

To this end my invention consists in the novel construction, arrangement, and combination of parts herein shown and described and more particularly pointed out in these claims.

In the accompanying drawings wherein like or similar reference characters indicate like or corresponding parts; Figure 1 is a side elevation of my device with the extended tongues for attaching horses to propel the machine broken away. Fig. 2 is a front elevation. Fig. 3 is a plan view. Fig. 4 is a section taken substantially on line 4—4 of Fig. 3. Fig. 5 is a section taken substantially on line 5—5 of Fig. 3. Fig. 6 is an enlarged detail showing the snapping rolls and associated parts. Fig. 7 is a plan view of the parts shown in Fig. 6. Fig. 8 is a section taken substantially on line 8—8 of Fig. 6. Fig. 9 is a detail showing the construction at the lower end of the snapping rolls. Fig. 10 is a partial section taken substantially on line 10—10 of Fig. 5. Fig. 11 is a detail of a portion of the mechanism shown in Fig. 10. Fig. 12 is a detail of a part of the lower end of the main elevator. Fig. 13 is a section taken substantially on line 13—13 of Fig. 3. Fig. 14 is a section taken substantially on line 14—14 of Fig. 6. Fig. 15 is a detail section taken substantially on line 15—15 of Fig. 3. Fig. 16 is a section taken substantially on line 16—16 of Fig. 3. Figs. 17, 18, 50 and 19 are details of the whip operating mechanism. Fig. 20 is an elevation of a modified form of husking mechanism. Fig. 21 is a plan view of the same. Fig. 22 is a section taken substantially on line 22—22 of Fig. 21. Fig. 23 is a side elevation showing a modi-

fied driving arrangement of the down corn lifting mechanism. Fig. 24 is a detail from Fig. 23, and Fig. 25 is a plan view of the driving mechanism shown in Fig. 23.

My device as shown in the drawings, consists of any desired number of supporting wheels, a frame mounted upon the wheels and adapted to properly support the various parts of my device in suitable coöperating position, a series of coöperating mechanisms each adapted to operate successively upon each stalk of corn or the ears after being detached therefrom, and means for attaching horses or otherwise propelling the device about a field when in operation.

In the form shown four supporting wheels are employed, the wheels 1—1 at the forward end of the frame 2 being each mounted in a suitable yoke 3 rigidly attached to the frame. The yokes 4—4 carrying the rear wheels 5—5 are each rotatably attached to a plate or turntable 6 which is in turn rigidly attached to the frame 2 thus providing for guiding my device by changing the position of the yokes 4 upon the plates 6. Any suitable means 80 may be employed to control the position of the yokes 4 to guide the mechanism. As shown an arm 7 is provided upon each yoke and connected by means of a rod 8. A shaft 9 is rotatably mounted in a convenient position upon the frame 2 and provided with a hand wheel 10 at its upper end and with an arm 11 at its lower end, the free end of the arm 11 being connected to the rod 8 by means of a link 12.

The series of coöperating mechanisms consists, first in means adapted to gather the stalks together and guide them into the succeeding portion of my device in suitable position, next means for removing the ears and husks from each stalk, then delivering the ears and husks to mechanism for removing and separating the ears from the husks, and lastly means for discharging the clean ears from the machine. Any suitable mechanism 100 may be employed to gather the stalks and direct them into suitable position in the machine. As shown a pair of slightly conical reels or rollers 14—14 are provided for each row of corn with their axis substantially parallel and inclined backward as shown. The lower end of each roller is preferably supported upon a suitable shoe 15 so formed that when carried close to the surface of a field its points will pass under any stalks of 110

corn which are broken down from any cause and guide the same into the space between the rollers 14 and against the lower portion of one or the other of the pair.

5 As my device is advanced through a field the rollers 14 are rotated in the direction indicated on the drawings and by engaging with the stalks tend to raise any down stalks into a vertical position. To increase this 10 tendency I preferably provide a spiral projection 16 upon the surface of each roller. This portion of my device also serves the purpose of gathering the grain and directing the same into the succeeding mechanism in 15 case the machine is not accurately guided on the rows or where the distance between the rows does not accurately correspond with the spacing of the machine. The shoe 15 is carried by suitable bars and braces 17, 18, and 19 which serve to assist in supporting the succeeding mechanism of my device.

Any suitable means may be employed to 20 rotate the rolls or reels 14. As shown the shafts 20 are extended beyond the upper end 25 of the rollers and provided with suitable bearings rigidly attached to the frame 2 with a sheave 21 connected by means of a belt or equivalent means 22 with a sheave 80 driven by suitable gearing 32 32' from the main shaft 24. Each pair of reels 14 are thus independently driven from the shaft 24 as clearly shown in Fig. 3.

In the modified form of my device shown 30 in Figs. 23, 24, and 25 bevel gears 21' are 35 provided upon each shaft 20 coöperating with gears 21"-21" upon a cross shaft 23 mounted in suitable bearings upon the frame 2. The shaft 23 is also provided with a sprocket 25 connected by suitable chain or 40 equivalent means 26 with a corresponding sprocket 27 connected to the forward wheels 1 of my device.

It is evident that in the last described form 45 the rotation of the reels 14 will bear an accurate relation to the forward movement of my machine. The stalks after being raised by the reels 14 are engaged by the snapping rolls 28. These rolls are substantially cylindrical in form and slightly conical at their 50 lower ends with their axes substantially parallel to the gathering reels 14 and adapted to be rotated in the direction indicated. The rolls 28 are arranged in pairs and so adjusted that while the stalks may pass between them 55 the ears upon the stalks cannot and will therefore be snapped off as they arrive at the rolls. This portion of the device may be arranged in any suitable manner. As shown the lower bearings for the rolls 28 are attached to the lower extremities of a yoke 29 60 attached to the frame 2, a bar 30 being provided extending from the bar 17 to the inner face of the bearing 31 to serve as a guide to accurately direct the stalks into the space 65 between the lower ends of the rolls 28. Any

suitable means may be provided to drive the snapping rolls 28. As shown the bevel gear 32 is mounted at the upper end of the inner roll 28 which is preferably slightly lower than the outer roll to which it is rotatably connected by means of the spur-gears 33 33', by this arrangement it will be noted that as the ears are snapped from the stalks they are directed towards the central portion of the machine where a suitably formed boot or receiver 34 is provided to receive them.

Any suitable additional means may be provided to insure the discharge of the detached ears into the receiver 34. In the form 70 shown a vibrator is provided above the outer roll of each pair of snapping rolls, adapted to engage the ears and force or knock them inward. This vibrator consists of a member 35 connected near either end by means of links 36, and 36' to the frame 2 and yoke 29 respectively. A shaft 37 is rotatably mounted in suitable bearings 38-38 upon the frame 2 and provided with an arm 39 for each vibrator. Suitable means are provided to partly rotate the shaft 37 and thus oscillate 80 the free end of the arm 39 which is connected by means of a link 40 to the member 35. By this means the member 35 is moved both longitudinally and transversely above the outer snapping rolls 28 thus beating the ears upon 85 stalks and tending to force the ears as soon as detached inwards toward the boot 34.

Any suitable means may be employed to 90 remove the ears from the boot 34 and deliver the same to the hopper or chute 41. In the form shown an elevator 42 is provided for 95 this purpose the head shaft 43 of which is driven by any suitable means from the main shaft 24 for example by the sprocket chain 81. Any suitable form of elevator may be 100 employed for this purpose.

As shown the back side of the boot 34 is 105 extended upward forming a back or bottom 44 the sides 83 of which may be employed to support the head shaft 43. In the form 110 shown these sides are each formed of two parts connected by bolts or equivalent means 84 each positioned in a slotted opening so that the sides may be slightly extended or shortened to adjust the position of the head 115 shaft. Suitable chains or equivalent means 45 are provided at each side of the bottom 44 connected at suitable intervals by means of flights or bars 46. Suitable guide sheaves or 120 idlers 47 and 48 being provided to so direct the chains 45 that the flights 46 sweep in close proximity to the bottom of the boot 34 and up the back 44 thus carrying any ears in the boot upward to the upper end of the back 125 where they fall by gravity into the chute or 130 hopper 41 and thence to the mechanism for removing the husks from the ears. Any suitable mechanism may be employed for this purpose. As shown one or more pairs of slightly inclined rolls 49 are provided of such

size and so adjusted that the husks upon an ear lying upon the rolls will be engaged and torn away without injuring the ear or breaking the kernels of the grain.

5 The several husking rolls may be rotated by any preferred means, in the form shown a gear 50 is provided at the upper end of each roll, and rigidly attached thereto, of suitable size to mesh with the corresponding gear upon 10 the next adjacent roll, a pair of sprocket wheels 51 and chain 52 or other suitable means being provided to transmit power from the shaft 24 to the train of gears 50—50.

Preferably the ears are delivered near the 15 upper ends of the rolls 49 and pass by gravity to their opposite ends during the husking operation. If desired, however, any desired number of rotary brushes or bristle rolls 53 may be arranged above the rolls 49 as shown 20 in Figs. 20 to 22 inclusive the bristles upon the several brushes being preferably arranged alternately in right and left hand spirals so that as the brushes are rotated, by means of suitable sprockets 54, chain 54' 25 gearing 55, and sprockets 56—56' and chain 57 from the main shaft 24, the engagement of the bristles with the ears will not only tend to move the ears toward the discharge end of the husking rolls but will also tend to rotate 30 the ears first in one direction then in the other as it encounters the successive brushes and also to raise the husks from the kernels so as to insure the complete removal of all husks from each ear.

35 The clean ears pass from the husking rolls 49 by a trough or slide 58 to an elevator 59 preferably extending over the side of my device and provided with a spout 60 to direct the clean ears into a wagon or other suitable 40 receptacle. The elevator 59 is also preferably driven by means of suitable sheaves 61, 62, and a belt or other suitable means 63 from the main shaft 24. Thus in the preferred form of my device all the mechanism 45 is driven primarily from the main shaft 24 which may in turn be driven in any convenient manner. In the form shown an independent gasoline engine, or other suitable motor 64 is mounted upon the frame 2 and 50 connected in any manner desired, as by sprockets 65—65' and chain 66 or other suitable transmission appliance, to the shaft 24.

Any desired means may be employed to 55 propel my device when in operation. As shown a portion 67—67' of the frame 2 extends to the rear and is there provided with suitable means for attaching horses or other draft animals which in a manner push my device before them thus avoiding any damage to 60 the unharvested corn from breaking down and trampling, obviously this is a great advantage as my device is thus enabled to operate in absolutely undisturbed grain.

Ordinarily it is difficult to keep draft animals pulling evenly with their driver seated

at their heads. To overcome this inconvenience a movable whip socket 68 is provided for each animal arranged to securely hold a small whip, or switch, so that a movement of the socket will bring the whip 70 sharply down upon the back or flank of a draft animal, a spring 82 or other suitable means being provided to normally hold each socket so that the whip contained therein is retracted. 75

A foot pedal 69 is provided for each whip socket and connected by means of a rod 70 or other suitable connector to the operating arm 71 of the socket so that a driver sitting in the seat 72 by the operation of a foot pedal 80 may instantly spur up any member of his lagging team.

Having thus described my improvement it is obvious that various immaterial modifications may be made in my device without departing from the spirit of my invention, hence I do not wish to be understood as limiting myself to the exact form or construction shown.

What I claim as new, and desire to secure by Letters Patent is:

1. In a device of the class described, corn gathering means comprising two substantially parallel pairs of rolls, each pair adapted to receive the stalks in a row between them and mounted to operate upon the stalks in a single row, in combination with a vibrator arranged in the rear of and within the lateral boundaries of each pair of rolls, and means for operating said rolls and the vibrators.

2. In a device of the class described, corn gathering mechanism comprising two substantially parallel pairs of rolls arranged in an inclined plane, each pair adapted to receive the stalks in a row between them and mounted to operate upon the stalks in a single row, the lower ends of the several rolls being positioned at a substantially uniform height, in combination with a vibrator positioned back of and within the lateral boundaries of each pair of rolls, and means for operating said rolls and the vibrators.

3. In a device of the class described, corn gathering mechanism comprising a plurality of substantially parallel rolls, arranged in pairs and in an inclined plane, with the lower ends of each pair advanced and positioned to operate upon the stalks in a single row, in combination with a vibrator mounted in rear of each pair of rolls to operate upon the stalks between the rolls of each pair, and means for operating the rolls and the vibrators.

4. In a device of the class described, corn gathering mechanism comprising a pair of tapering rolls arranged in an inclined plane with their lower ends advanced, each roll provided with a spiral projection adapted to lift and direct a stalk between the rolls when

the same are rotated toward each other, in combination with a second pair of rolls positioned substantially parallel to and behind said gathering rolls, a vibrator positioned 5 between the pairs of rolls, and means for operating the rolls and said vibrator.

5. In a device of the class described, corn gathering mechanism comprising a pair of tapering rolls arranged in an inclined plane 10 with their lower ends advanced, each roll being provided with a spiral projection adapted to lift and direct a stalk between the rolls when the same are rotated toward each other, in combination with a pair of snapping rolls positioned parallel to and behind said gathering rolls, means for rotatively connecting the upper ends of said gathering rolls to the upper ends of said snapping rolls, a vibrator positioned between the pairs 15 of rolls, and means for operating the rolls and vibrator.

6. In a corn harvesting machine, gathering means comprising a pair of tapering rolls adapted to be rotated toward each other, 20 said rolls being arranged in an inclined plane with their lower ends advanced, each roll being provided with spiral projections to lift and direct a stalk between them, a vibrator positioned behind the rolls and within the 25 lateral boundaries thereof, means for rotating the rolls, and a shoe positioned at the lower end of each roll to assist in supporting the same and to direct the stalks to the lower end of the rolls.

30 7. In a corn harvesting machine, means for simultaneously removing the ears from a plurality of rows of stalks, comprising a pair of substantially parallel rolls for each row suitably spaced from each other, with the inner 35 roll of each pair arranged in a plane slightly lower than the plane of the other roll, and a vibrator positioned above said rolls and adapted to simultaneously operate both longitudinally and transversely thereof, in 40 combination with means for rotating said rolls and means for operating said vibrator.

8. In a corn harvesting machine, means for simultaneously removing the ears from a plurality of rows of stalks, comprising a pair of substantially parallel rolls for each row, suitably spaced from each other, with the inner 50 roll of each pair arranged in a plane slightly lower than the plane of the other roll, and means for directing the stalks into the space between the rolls, and a vibrator positioned above said rolls and adapted to simultaneously operate both longitudinally and transversely thereof, in combination with means for rotating said rolls and means for operating 55 said vibrator.

9. In a device of the class described, corn gathering mechanism comprising a pair of gathering rolls arranged in an inclined plane with their lower ends advanced to receive the stalks in a row between them and mounted 60 to operate upon the stalks in a single row, a second pair of rolls positioned substantially parallel to and behind said gathering rolls, a vibrator positioned between the pairs of 65 rolls, means for rotating the rolls, and means for operating the vibrator.

10. In a device of the class described, corn gathering mechanism comprising a pair of tapering gathering rolls arranged in an inclined plane with their lower ends advanced 70 to receive the stalks in a row between them and mounted to operate upon the stalks in a single row, a second pair of rolls positioned substantially parallel to and behind said gathering rolls, a vibrator positioned between the pairs of 75 rolls, adapted to simultaneously operate both longitudinally and transversely thereof, means for rotating the rolls, and means for operating the vibrator.

In testimony whereof, I have hereunto 80 signed my name in the presence of two subscribing witnesses.

WILLIAM SEWARD BAIRD.
